UNITED STATES PATENT OFFICE.

HENRY R. SCHWEINLER, OF BROOKLYN, NEW YORK, ASSIGNOR, BY DIRECT AND MESNE ASSIGNMENTS, TO W. T. MACON, ADMINISTRATOR OF JACOB H. MACON, JR., DECEASED, OF TAMPA, FLORIDA, AND FRANK M. SIMONTON.

SPEED-CONTROLLER FOR SEWING-MACHINES.

No. 821,129.

Specification of Letters Patent.

Patented May 22, 1906.

Application filed May 4, 1905. Serial No. 258,776.

To all whom it may concern:

Be it known that I, HENRY R. SCHWEINLER, a citizen of the United States, residing at Brooklyn, in the county of Kings and State of New York, have invented a new and useful Speed-Controller for Sewing-Machines, &c., of which the following is a specification.

The invention relates to improvements in speed-controllers for sewing-machines, &c.

10 The object of the present invention is to improve the construction of devices for controlling speed and to provide a simple, inexpensive, and efficient speed-controller designed for use on sewing-machines and light 15 machines and capable of enabling the speed of such machines to be controlled and varied as desired.

20 A further object of the invention is to provide a speed-controller of this character having a continuously-operating adjustable motor and a shiftable wheel, both the motor and the shiftable wheel being adapted to vary the speed and the shiftable wheel being also adapted when released by the operator to automatically throw out of operation the sewing-machine or other machine driven by the speed-controller.

25 With these and other objects in view the invention consists in the construction and 30 novel combination and arrangement of parts hereinafter fully described, illustrated in the accompanying drawings, and pointed out in the claims hereto appended, it being understood that various changes in the form, proportion, size, and minor details of construction 35 within the scope of the claims may be resorted to without departing from the spirit or sacrificing any of the advantages of the invention.

40 In the drawings, Figure 1 is a side elevation, partly in section, of a speed-controller constructed in accordance with this invention. Fig. 2 is a plan view of the same. Fig. 3 is an end elevation of the speed-controller.

45 Fig. 4 is a transverse sectional view taken substantially on the line 4-4 of Fig. 1. Fig. 5 is a detail sectional view taken substantially on the line 5-5 of Fig. 1, illustrating the means for moving the shiftable wheel.

Like numerals of reference designate corresponding parts in all the figures of the drawings. 50

1 designates a frame designed to be secured to the lower face of the table or top 2 of a sewing-machine frame and provided with 55 upwardly-extending arms 3 and 4, arranged in pairs and spacing the body portion of the frame 1 from the table or top 2. The body portion of the frame 1 is horizontal, and depending therefrom is a pair of bearing-brackets 5 and 6, located at one end of the frame 1 and at an intermediate point on the same and secured to the frame by screws or other suitable fastening devices; but the bearing-brackets 5 and 6 may be made rigid with the 60 frame 1 in any other desired manner.

65 Journaled in suitable bearings of the depending brackets or arms 5 and 6 is a horizontal driven shaft 7 of transmitting mechanism or mechanism for transmitting motion 70 from the gear to the machine to be operated, and the said shaft is arranged above and in parallelism with the upper face of a horizontal friction-wheel 8 and has mounted on it a shiftable wheel 9, adapted to be moved by 75 the means hereinafter described outwardly and inwardly relative to the horizontal friction-wheel 8 for varying the speed of the driven shaft 7. The driven shaft 7 is provided with a longitudinal groove, and the 80 shiftable wheel is slidably interlocked with the shaft 7 by means of a key 10 or the like.

85 The horizontal friction-wheel is mounted on a vertical spindle 11 of the depending arm or bracket 6, and it has a hub or extension 12 at its lower face, which is provided with a ball-bearing for reducing to a minimum the friction resulting from the end thrust of the hub or extension 12. The upper end of the spindle is threaded into a suitable socket of the depending arm or bearing 6, and its lower end is threaded for the reception of a nut 13, a washer 14 being interposed between the nut and the lower end of the hub or extension 12. 90

95 The horizontal friction-gear is provided at or near its center with an annular recess 15, adapted to receive the shiftable wheel 9, as indicated in Fig. 1 of the drawings, whereby

the transmission of motion from the horizontal gear 8 to the driven shaft 7 is interrupted and the sewing-machine is thrown out of operation. The shiftable wheel is adapted to 5 be moved outwardly from the recess 15 by foot-power, and as soon as it is released by the operator it is automatically returned to its position above the recess 15 by a coiled spring 16. The shiftable wheel is provided 10 with a hub or extension having an annular groove 17 and adapted to receive a forked shifting arm 18 of a slide 19. The slide 19 consists of a sleeve arranged on a guide-rod 20 and connected with a suitable treadle (not 15 shown) by a flexible cord 21, which passes over a guide pulley or wheel 22, located at the outer end of the guide-rod 20 and mounted on a suitable shaft or spindle, preferably carried by the outer bearing-bracket 5. The 20 guide-rod is supported by depending arms or brackets 5 and 6, and the slideable sleeve 19 is also connected with the spring 16, which is secured to a pin or projection 23, which depends from the frame 1. By this construction 25 the flexible connection 21 is adapted to be operated to move the shiftable wheel outwardly, and the spring is adapted to move the shiftable wheel inwardly as the flexible connection is released. The desired speed 30 may thus be obtained from the horizontal gear. The outer end of the driven shaft 7 carries a grooved pulley 24, which receives a suitable belt 25 for operating the sewing-machine or other machine to which the speed- 35 controller is applied. The belt 25, which is indicated in dotted lines in Fig. 3 of the drawings, has its front stretch held out of engagement with the mechanism of the sewing-machine by an adjustable idler or guide-pulley 40, mounted on the stub-shaft 27 of an adjustable sleeve 28. The sleeve 28 is arranged to slide on a transversely-disposed outwardly-projecting arm or pin 29 and is secured in its adjustment by a clamping-screw 45 30, as clearly illustrated in Fig. 2 of the drawings.

The shiftable wheel is designed to be constructed of fiber, rubber, rawhide, or other suitable material, and motion is communicated 50 to the horizontal gear by means of a drive-wheel 31, designed to be constructed of rubber, rawhide, or the like, similar to the shiftable wheel. The drive-wheel is mounted on the drive-shaft 31^a of an adjustable 55 motor 32, which is preferably electric, but which may be of any other preferred type. The motor-casing is provided at opposite sides with projecting portions or lugs 33, having openings for the reception of horizontal 60 guide-rods 34, located at opposite sides of the frame 1, as clearly shown in Fig. 2 of the drawings, and secured at their ends to suitable lugs or projections 35 and 36. The motor is slidable inwardly and outwardly on the

guides to carry the drive-wheel radially of 65 the horizontal friction-wheel 8 for arranging the drive-wheel the desired distance from the center of the gear 8 to secure approximately the desired speed. The motor is adjusted by means of a screw 36^a, provided with a hand-wheel 37, and swiveled at one end to a yoke 38, and engaging at its opposite end a threaded opening 39 of a fixed projection or arm 40 of the frame 1, whereby when the screw is rotated the motor will be moved inwardly or 70 outwardly, according to the direction of the rotation of the screw. The yoke consists of a transverse portion and sides, which are secured by screws 41 or other suitable fastening devices to the lugs or enlargements of the 75 motor-casing 32, and which are provided with projections 42 to fit against the lugs or enlargements 33, as clearly illustrated in Fig. 1 of the drawings. By this construction the yoke is rigidly connected to the motor-casing. The transverse portion of the yoke 38 is provided with a centrally-arranged depending ear 43 to receive the swiveled end of the shaft. The shaft, as indicated in dotted lines in Fig. 2 of the drawings, is preferably 80 provided with a head for engaging the outer face of the ear 43, and the hand-wheel, which is secured to the shaft by a suitable fastening device 44, engages the inner face of the ear 43. 85

The motor may be continuously operated 90 while the sewing-machine is in use, and it does not have to be stopped each time the sewing-machine is stopped, as the stop of the latter is effected by the automatically-operating coiled spring, which carries the shiftable wheel to the groove or recess of the friction-gear. It is only necessary to start the motor when it is desired to use the sewing-machine and stop the motor when one is through 95 with the machine. By means of the adjustable motor and the shiftable wheel a large variety of speeds may be obtained for adapting a sewing-machine or other machine to the particular character of the work to be performed. 100

Having thus fully described my invention, what I claim as new, and desire to secure by Letters Patent, is—

1. In a device of the class described, the combination of a sewing-machine frame, a 115 horizontal supporting-frame located beneath the top of the sewing-machine frame and provided with upwardly-extending arms secured to the said top, a horizontal gear, an adjustable motor slidably hung from the horizontal supporting-frame and having a driving-wheel engaging the horizontal gear, said motor being movable to carry the driving-wheel toward and from the center of the driving-gear, and means for transmitting motion 120 from the gear to the sewing-machine. 125

2. In a device of the class described, the combination of a horizontal frame provided

with depending lugs, guide-rods supported by the lugs and spaced from the frame, a gear, a motor provided at the top with opposite lugs 5 slidable on the guide-rods, whereby the motor is hung therefrom, said motor being also provided with a drive-wheel movable toward and from the center of the gear, and means for transmitting motion from the gear to the machine to be operated.

10 3. In a device of the class described, the combination of a horizontal frame provided with upwardly-extending arms adapted to be secured to the frame of a machine, said horizontal frame being also provided with depending lugs, a gear, guide-rods supported by the 15 said lugs and spaced from the frame, a motor provided at the top with lugs slidable arranged on the guide-rods, whereby the motor is hung from the horizontal frame, said 20 motor being also provided with a drive-wheel movable toward and from the center of the gear, and means for transmitting motion from the gear to the machine to be operated.

4. In a device of the class described, the 25 combination with a horizontal frame, a horizontal gear, and a motor slidably hung from the frame and provided with a drive-wheel movable toward and from the center of the gear, of a bracket depending from the frame 30 and having a threaded opening, an adjusting-screw connected with the motor and engaging the threaded opening of the bracket, and means for transmitting motion from the gear to the machine to be operated.

35 5. In a device of the class described, the combination of a frame having opposite guides, a motor provided at the upper portion with lugs slidable on the guides, said motor being also provided with a drive-wheel, 40 a gear, a bracket located above the gear and depending from the frame and having a threaded opening, a yoke secured to one of the lugs of the motor, an adjusting-screw swiveled to the yoke and engaging the threaded 45 opening of the bracket for moving the drive-wheel toward and from the center of the gear, and means for transmitting motion from the gear to the machine to be operated.

6. In a device of the class described, the 50 combination of a frame, inner and outer bearing-brackets depending from the frame, a gear supported by the inner bearing-bracket, a shaft mounted on and extending across the space between the bearing-brackets, a shiftable wheel mounted on the shaft and movable toward and from the center of the gear, a guide-rod also supported by and extending across the space between the bearing-brackets, a slide mounted on the guide-rod and connected with the shiftable wheel, and means for operating the slide.

55 7. In a device of the class described, the combination of a frame, inner and outer bearing-brackets depending from the frame,

a gear supported by the inner bearing-bracket, a shaft mounted on and extending across the space between the bearing-brackets, a shiftable wheel mounted on the shaft and movable toward and from the center of the gear, a guide-rod also supported by and extending across the space between the bearing-brackets, a slide mounted on the guide-rod and connected with the shiftable wheel, and means for operating the slide, 65 said means embodying a guide-pulley located at the outer bearing-bracket, and a flexible connection arranged on the guide-pulley and connected to the slide.

8. In a device of the class described, the combination of a frame, inner and outer 80 bearing-brackets depending from the frame, a gear supported by the inner bearing-bracket, a shaft mounted on and extending across the space between the bearing-brackets, a shiftable wheel mounted on the shaft and movable toward and from the center of the gear, a guide-rod also supported by and extending across the space between the bearing-brackets, a slide mounted on the guide-rod and connected with the shiftable wheel, and 85 means for operating the slide, said means embodying a guide-pulley located at the outer bearing-bracket, a flexible connection connected with the guide for moving the same 90 outward, and a spring connected with the 95 slide for moving the same inward.

9. In a device of the class described, the combination of a frame provided at one end with horizontal guide-rods, inner and outer bearing-brackets located at the opposite end 100 of the frame, a motor hung from and slidable on the guide-rods and having a drive-wheel, a horizontal gear supported by the inner bearing-bracket and receiving the drive-wheel, a 105 shaft extending across the space between and supported by the bearing-brackets, a shiftable wheel slidable on the shaft and arranged to engage the gear, a guide-rod also supported by the bearing-brackets, a slide mounted on the guide-rod and connected with the 110 shiftable wheel, means for operating the slide, and operating mechanism located above the gear and arranged between the inner bearing-bracket and the motor for adjusting the latter 115 to move the drive-wheel toward and from the center of the gear.

10. In a device of the class described, the combination with a gear, of a drive-wheel engaging the gear, means for moving the drive-wheel toward and from the center of the gear for varying the speed of the same, and transmitting mechanism having a shiftable wheel movable toward and from the center of the gear independently of the driving-gear for varying the speed.

11. In a device of the class described, the combination of a gear, means for rotating the same, a shaft, a shiftable wheel thereon

for engaging the said gear, a pulley carried by the shaft, and an adjustable guide-pulley moved inwardly and outwardly.

12. In a device of the class described, the combination of a gear, means for rotating the same, a shaft, a shiftable wheel thereon for engaging the said gear, a pulley carried by the shaft, an adjustable guide-pulley moved inwardly and outwardly, a slide carrying the

guide-pulley, and guiding means for the slide.

In testimony that I claim the foregoing as my own I have hereto affixed my signature in the presence of two witnesses.

HENRY R. SCHWEINLER.
